2,654,950

SUCTION HOOD HOLDER

Bert J. Daigle, Sulphur, La., assignor of one sixty-fourth to Ellis Woody Thompson, Calcasieu Parish, La.

Application May 1, 1952, Serial No. 285,494

4 Claims. (Cl. 32—58)

1

This invention relates in general to holders, and more particularly to a holder for a suction hood utilized in combination with a dental machine.

The primary object of this invention is to provide a suction hood holder for a suction hood adapted to be mounted adjacent a patient's mouth for removing abrasives therefrom during the process of drilling teeth with a fluid blast drill.

Another object of this invention is to provide an improved suction hood holder for holding a suction hood of a dental machine in a patient's mouth and thereby eliminating the use of an assistant for holding the suction hood.

Another object of this invention is to provide an improved suction hood holder which is adapted to be mounted on a dental machine or other supporting structure adjacent a dental chair for holding a suction hood of the dental machine, said holder permitting stability of the suction hood and permitting the same to be moved in various positions with respect to a patient seated in a dental chair.

Another object of this invention is to provide an improved support which is adapted to be secured to a dental machine for supporting a suction hood in the proper position with respect to a patient's mouth, said support being of a simple construction whereby it may be quickly and easily mounted and at the same time permits the suction hood to be moved and retained in the desired position.

A further object of this invention is to provide an improved suction hood holder for a suction hood of a dental machine, said holder providing a stable support for the suction hood and thereby permitting maximum abrasive covering when utilized in combination with a fluid blast drill.

With these objects definitely in view, this invention resides in certain novel features of construction, combination and arrangement of elements and portions as will be hereinafter described in detail in the specification, particularly pointed out in the appended claims, and illustrated in the accompanying drawings which form a material part of this application and in which:

Figure 1 is a perspective view of a dental machine provided with a suction line and a suction hood, the suction hood being supported in the suction hood holder, which is the subject of this invention, the suction hood holder being mounted on the dental machine;

Figure 2 is an enlarged side elevational view of the suction hood holder of Figure 1 and shows the structure of a preferred form of suction hood supporting clamp;

2

Figure 3 is a top plan view of the suction hood holder of Figure 2 and shows the general construction thereof;

Figure 4 is an enlarged fragmentary transverse horizontal sectional view taken substantially upon the plane indicated by the section line 4—4 of Figure 2 and shows the manner in which the telescoping arm of the suction hood holder is pivotally mounted between a pair of spaced parallel plates;

Figure 5 is an enlarged fragmentary transverse vertical sectional view taken substantially upon the plane indicated by the section line 5—5 of Figure 3 and shows the general relationship of the inner end of the telescoping arm with respect to the spaced plates;

Figure 6 is a side elevational view of the other end of the telescoping arm of the suction hood holder and shows a modified form of suction hood supporting clamp; and

Figure 7 is a fragmentary perspective exploded view of the outer end of the telescoping arm and shows the construction of still another modified form of suction hood supporting clamp.

Similar characters of reference designate similar or identical elements and portions throughout the specification and throughout the different views of the drawings.

Referring now to the drawings in detail, it will be seen that there is illustrated in Figure 1 a dental machine, which is referred to in general by the reference numeral 10, intended for use with a fluid blast drill for drilling teeth. The dental machine 10 includes a suction line 12 which has mounted on its outer end a suction hood 14, the suction hood 14 being adapted to be mounted in a patient's mouth for removing abrasive material therefrom during the process of drilling teeth with the fluid blast drill. In order that the suction hood 14 may be suitably positioned with respect to a patient's mouth during the drilling operation, the dental machine 10 is provided with a suction hood holder, which is referred to in general by reference numeral 16.

Referring now to Figures 2 and 3 in particular, it will be seen that the suction hood holder 16, which is the subject of this invention, includes a telescoping arm, which is referred to in general by the reference numeral 18, which is connected to a mounting bracket, which is referred to in general by the reference numeral 20, by a swivel connection, which is referred to in general by the reference numeral 22. The telescoping arm 18 has secured to the free end thereof a suction hood supporting clamp 24. It will be noted that the telescoping arm 18 includes an elongated

tubular member 26 in which is telescopically received the inner end of an elongated rod 28. The elongated rod 28 may be extended with respect to the tubular member 26 and is retained in an adjusted position by a locking screw 30 which is threadedly engaged in an internally threaded bore of a boss 32 carried by the upper side of the tubular member 26 at the outer end thereof.

The mounting bracket 20 includes a first arm 34 which is provided with a plurality of spaced apertures 36, the apertures 36 receiving fasteners 38 which secure the arm 34 to the dental machine 10. The mounting bracket 20 also includes an arm 40 which is at right angles to the arm 34 to which the swivel connection 22 is secured.

The swivel connection 22 includes a vertically extending sleeve 42 which is secured at its midpoint to the free end of the flange 40. Secured to the upper and lower ends of the sleeve 42 are inwardly turned telescoped ends 44 and 46 of spaced parallel vertically extending plates 48 and 50, respectively. The inwardly turned ends 44 and 46 of the plates 48 and 50, respectively, are pivotally secured to the sleeve 42 by a vertically extending fastener 52 which extends through both the sleeve and the ends. The fastener 52 is provided with a knurled head 54 at the upper end thereof and is threadedly engaged with a nut 56 carried by the lowermost inwardly turned end 46 of the plate 50. When the fastener 52 is loosely disposed within the sleeve 42, the plates 48 and 50 are free to pivot about a vertical axis through the center of the fastener 52. When it is desired to lock the plates 48 and 50 with respect to the sleeve 42 and associated flange 40, the fastener 52 is threaded further into the nut 56 so as to produce a clamping action.

Referring now to Figure 4 in particular, it will be seen that the spaced parallel plates 48 and 50 are provided adjacent their other ends with a transversely extending fastener 58 which passes through a bore 60 in the plate 50 and is threadedly engaged in an internally threaded bore 62 in the plate 48, the bores 60 and 62 being horizontally aligned. In order that rotation of the fastener 58 may be facilitated, it is provided with a knurled head 64. The fastener 58 also passes through aligned bores 66 in the inner end of the tubular member 26, which is disposed between the spaced parallel plates 48 and 50.

In order that the tubular member 26 may be properly supported between the spaced parallel plates 48 and 50 and also clamped in an adjusted position, there is also mounted on the fastener 58 a pair of cup-shaped members 68 which abut each other and their respective plates 48 and 50, the cup-shaped members 68 retaining the plates 48 and 50 in spaced parallel relation. The cup-shaped members 68 are provided with aligned recesses in which is received the inner end of the tubular member 26, the inner end of the tubular member being rigidly supported by the cup-shaped members 68 for rotation about the horizontal axis passing through the center of the fastener 58. It will be understood that the cup-shaped members 68 rotate when the tubular member 26 of the telescoping arm 16 is pivoted and that the telescoping arm 16 may be secured in an adjusted relation by tightening down upon the fastener 58 to clamp the cup-shaped members 68 between the spaced parallel plates 48 and 50.

Referring now to Figures 2 and 3 in particular, it will be seen that the suction hood supporting clamp 24 is in the form of a generally U-shaped

spring clamp which has secured to the rear side thereof a ball 72 which is mounted in a socket 74 at the other end of the elongated rod 28 to form a ball and socket connection. The ball 72 is of such a size whereby it may be removed from the socket 74 and, therefore, is retained within the socket 74 by a locking screw 76 threadedly engaged in an internally threaded bore of a boss 78 mounted on the upper side of the socket housing 80. It will be understood that the locking screw 76 also clamps the ball 72 in an adjusted position within the socket 74, whereby the angle of the suction hood supporting clamp 24 may be varied with respect to the telescoping arm 16.

Referring now to Figure 6 in particular, it is seen that there is illustrated a modified form of suction hood support clamp, which is referred to in general by the reference numeral 82. The suction hood supporting clamp 82 is generally cylindrical in outline and has a pair of spaced parallel flanges 84 to form a split ring clamp. Carried by the flanges 84 is a fastener 86 for urging the flanges 84 together to provide a clamping action. The suction hood supporting clamp 82 has secured to one side thereof a ball 88, which is identical to the ball 72 of the suction hood supporting clamp 24, received within the socket 74 of the socket housing 80 mounted at the outer end of the elongated rod 28. It will be understood that the ball 88 is retained within the socket 74 by the locking screw 76 in the manner set forth relative to the ball 72.

Referring now to Figure 7 in particular, it will be seen that there is illustrated still another modified form of suction hood supporting clamp, which is referred to in general by the reference numeral 90. The suction hood supporting clamp 90 includes a pair of clamp halves 92 and 94 which are semi-circular and have outwardly extending flanges 96 and 98, respectively, at the ends thereof. The clamp halves 92 and 94 are secured together by fasteners 100 which pass through apertures 102 in the flanges 98 and are threadedly engaged in threaded apertures 104 in the flanges 96. The clamp half 92 is provided with a ball 106, which is similar to the balls 72 and 88, and is secured within the socket 74 of the housing 80 by the locking screws 76.

While the mounting bracket 20 has been illustrated and described as being connected to the dental machine 10, it will be understood that it is not intended to so limit the invention as the mounting bracket 20 may be equally as well secured to a wall or other supporting structure adjacent a dental chair, however, it will be understood that regardless as to what structure the mounting bracket 20 is secured, the relationship of the suction hood holder 16 with respect to a patient seated in a dental chair must be such that the suction hood 14 may be held in the proper position relative to the patient's mouth. It will be understood that the various adjustments of the suction hood holder 16 permit the mobility of the suction hood and adapt the same to be positioned as desired with respect to the patient in the dental chair, and at the same time provide a stable support for the suction hood 14 when placed in a position so as to eliminate the requirement for an assistant to hold the suction hood and allow the suction hood to be positioned for maximum recovery of the basic materials utilized in the drilling process.

The operation of this device will be understood from the foregoing description of the details thereof, taken in connection with the above re-

cited objects and drawings. Further description would appear to be unnecessary.

Minor modifications of the device, varying in minor details from the embodiment of the device illustrated and described here, may be resorted to without departure from the spirit and scope of this invention, as defined in the appended claims.

Having described the invention, what is claimed as new is:

1. In combination with a dental machine including a suction hood utilized in combination with a fluid blast drill, a support for a suction hood carried by said dental machine for removing abrasive material from the mouth of a patient, said support including a mounting bracket secured to the dental machine, a telescoping arm swivelly connected to said mounting bracket, a suction hood supporting clamp mounted at the outer end of said telescoping arm, said suction hood being retainable in position relative to a patient's mouth by said support.

2. In combination with a dental machine including a suction hood utilized in combination with a fluid blast drill, a support for a suction hood carried by said dental machine for removing abrasive material from the mouth of a patient, said support including a mounting bracket secured to the dental machine, a telescoping arm swivelly connected to said mounting bracket, a suction hood supporting clamp mounted at the outer end of said telescoping arm, said suction hood supporting clamp being secured to the outer end of said telescoping arm by a ball and socket joint, said suction hood being retainable in position relative to a patient's mouth by said support.

3. In combination with a dental machine including a suction hood utilized in combination with a fluid blast drill, a support for a suction hood carried by said dental machine for removing abrasive material from the mouth of a patient, said support including a mounting bracket secured to the dental machine, a telescoping arm swivelly connected to said mounting bracket, a suction hood supporting clamp mounted at the

outer end of said telescoping arm, said suction hood supporting clamp being secured to the outer end of said telescoping arm by a ball and socket joint, the socket being mounted on said telescoping arm and said ball being mounted on the suction hood supporting clamp, said ball being removable from said socket, said suction hood being retainable in position relative to a patient's mouth by said support.

4. In combination with a dental machine including a suction hood utilized in combination with a fluid blast drill, a support for a suction hood carried by said dental machine for removing abrasive material from the mouth of a patient, said support including a mounting bracket secured to the dental machine, a telescoping arm swivelly connected to said mounting bracket, a suction hood supporting clamp mounted at the outer end of said telescoping arm, said suction hood supporting clamp being secured to the outer end of said telescoping arm by a ball and socket joint, the socket being mounted on said telescoping arm and said ball being mounted on the suction hood supporting clamp, said ball being removable from said socket, a swivel connection between said telescoping arm and said mounting bracket including a pair of plates having overlapping rear end portions, said rear end portions being pivotally connected to said mounting bracket, the inner end of said telescoping arm being positioned between said plates and connected thereto for pivotal movement, said suction hood being retainable in position relative to a patient's mouth by said support.

BERT J. DAIGLE.
